UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

BUTTON CLAMP.

Application filed August 4, 1924. Serial No. 729,881.

This invention relates to button clamps for button sewing machines particularly of that type which employs a single thread, though many features are well adapted for 5 other types of button sewing machines.

In a single thread machine if the last two strokes of the needle in sewing a button are passed through the same hole of the button and the work, the thread is knotted. It is 10 therefore desirable that the button be so engaged by the clamp as to be positively lifted at the end of the sewing operation so as to break the thread after the knot has been tied, to release the work from the machine. 15 It is also important that the button be held down against the work during the sewing operation.

To accomplish both these actions this invention provides a construction having jaw 20 portions engaging both the upper and lower faces of the button, so constructed that they may conform automatically to buttons of different thickness without requiring adjustment. These jaw portions are also constructed so as to facilitate placing the buttons in position so that the time required 25 for the operator to place successive buttons in position is reduced to the minimum.

Further it provides a construction where- 30 by buttons of irregular thickness may be successfully and expeditiously handled, provision being made to prevent excessive tilting of the buttons even though they may be very irregular in thickness.

Mechanism is provided also by which the spacing of the jaws is readily adjusted to conform to buttons of different diameters.

The clamp may be used for either two or 40 four hole buttons and, as when the four hole buttons are used there is a relative movement between the button and the sewing instrumentalities when changing from one set of two holes to the other set of two holes, means may be provided for preventing 45 the buttons from being pulled from between the jaws when this relative movement takes place in case this should be found necessary or desirable.

Further features and advantageous de- 50 tails and combinations of parts will appear from a more complete description of an embodiment of the invention disclosed in the accompanying drawings, in which—

Figure 1 is a fragmentary plan partly in side elevation and partly in longitudinal

section of a single thread sewing machine employing the clamp of this invention.

Figure 2 is a plan of a two hole button.

Figures 3 and 4 are sections on lines 3—3 and 4—4, respectively, of Figure 2. 60

Figure 5 is a plan of a four hole button of a different size than the button shown in Figures 2, 3 and 4.

Figure 6 is a section on line 6—6 of Figure 5. 65

Figure 7 is a front elevation of the clamp.

Figure 8 is a bottom plan of the forward portion thereof.

Figure 9 is a detail perspective of portions of two of the clamping jaws. 70

Figure 10 is a detail section similar to a portion of Figure 1, but showing a four holes buttons with the threads passed through two holes only.

Figure 11 is a similar view showing the 75 button moved into position for the succeeding stitches to pass through the other two holes.

Figures 12, 13 and 14 are front and side elevations, and a plan view, respectively, of 80 a button supporting and lifting element.

Referring to these drawings, first to Figure 1, 1 indicates the bed of the machine having a work or cloth plate 2 on which the work is supported and over which extends the head 3 of the machine in which is mounted for vertical reciprocative and laterally oscillatory movement, a needle bar 4 carrying a needle 5. Beneath the work plate and the machine head 1 is a looper 90 mechanism 6. These parts shown are of the type disclosed in my prior application for patent, Serial Number 633,625, filed April 21, 1923, for button sewing machine. The button clamp indicated generally at 10 is 95 shown as fixed to the forward end of an arm 11, the rear end of which is bent downwardly as at 12 and may be pivoted at 13 to a fixed lug 14 when it is desired to sew two hole buttons, or its lower end as at 15, may 100 be fixed to a slide movable lengthwise of the base of the machine and carrying the work plate, all as disclosed in the application above referred to, the former connection being employed when two hole buttons are to be sewed and this latter connection being employed when it is desired to sew four hole buttons since it permits the button and the work to be moved lengthwise to bring the two pairs of holes of a four hole 105

110

button successively in line with the sewing instrumentalities including the needle and the looper. Whether the arm 11 is connected to the fixed lug or to the slide it may 5 be raised upwardly, tilting about its pivotal connection with either one of these members to raise its forward end and the button, as will later appear, from the work. For the purpose of raising it a chain 20 is 10 connected at 21 to the forward end of the arm 11, this chain extending to any suitable raising mechanism, usually treadle operated, in the usual manner.

The clamp itself comprises a supporting plate 25 fixed to the forward end of the arm 11 and having pivoted to its under side on the pivots 26 (see Figures 1 and 8) a pair of side jaw members 27. These jaws comprise bars having their forward ends down 15 turned as at 28 and then, as shown best in Figures 8 and 9, bent inwardly or toward each other as at 29. The adjacent ends of these bars, as at 30, are formed for engagement with substantially opposite edge portions 20 of the buttons and in order that the buttons may be held down to the work, each is provided with an end flange or lip 31 adapted to project over the upper face of the button in position therebetween. Fixed 25 to the portion 28 of each of these jaws is a leaf spring arm 32 (shown detached in Figures 12 to 14), attaching means for these springs being shown as the studs 33. Each spring arm passes down the rear of a jaw portion 28 and beneath the forwardly directed portion 34 of the jaw, their inner ends being turned toward each other and extending beyond the edge portions 30 to form button supporting lips as at 35. This 30 lip portion 35 also extends forwardly of the jaw portion 29 as at 36 in order to furnish a shelf on each side on which the buttons may be placed and slid rearwardly into position beneath the upper lips 31. Each 35 spring arm 32 is so designed that its portion 35 is normally held up against the under face of the jaw portion 34, but it is permitted to yield downwardly therefrom to an extent limited by a finger 38 bent up 40 from its edge and overlying the upper face of the jaw portion 29. The spring arms may thus yield to permit buttons of varying thicknesses to be placed in position between them and the lips 31, but on raising the button clamp these arms are not permitted to 45 separate from the jaw members 29 further than permitted by the fingers 38 engaging their upper faces. Sufficient motion is permitted, however, to provide for the various 50 thickness of buttons which it is desired to sew, the resiliency of these arms causing them to conform automatically to the thinner buttons and press them up against the lips 31. By causing these button-supporting arms to move up positively after a pre-

determined extent of resilient motion, the buttons are raised positively from the work table when the button clamp is raised and the thread is broken.

In order to hold these springs in proper 70 relation to the ends of the button clamp they may be provided with upstanding pins 39 which may play up and down in suitable openings 390 in the portions 29 of the jaws.

Cooperating with these side jaws is a rear 75 jaw 40 having its end 41 shaped to engage the edge of the button and being provided with a groove such as 42 in substantially the same plane as the flanges 31. The edges of groove 42 form elements which extend over 80 and under the button when it is placed between the jaws and it prevents the rear edge thereof from tilting up or down to an extent sufficient to interfere with proper sewing of the button. The three jaws thus 85 have a three point support about the periphery of the button on its upper side which tends to hold it sufficiently level for the needle to pass through the sewing holes thereof even though the button may be quite 90 irregular in thickness. The rear jaw 40 is fixed to a plate 45 slidable on the lower face of the plate 25. This plate 45 is held beneath the jaws 27, retaining them against the lower face of the plate 25, by means of a 95 screw 46 passing through a slot in this plate 25 and threaded into the plate 45 between the jaw member 27. This plate 45 is provided with a pair of converging slots 50 in which ride pins 51 projecting downwardly 100 from the jaw members 27, these slots being so disposed that as the plate 45 is slid forwardly, bringing the rear jaw member 40 therewith, the side jaws are moved toward each other by the pins 51 riding into the 105 more nearly adjacent ends of the slots.

The forward portions of the jaws 27 may be held against the lower face of the plate 25 by means of a T-shaped retaining plate 110 80 fixed at its central portion by a screw 81 to the forward end of the plate 25, the laterally extended portions 82 of this plate being spaced from the lower face of the plate 25 a sufficient distance for the jaws to pass 115 therebetween.

In order that these jaws may be brought resiliently together to engage buttons of different diameters, means is provided for resiliently urging the plate 45 forwardly. As shown this is done by means of a plunger 120 55 having a reduced portion 56 about which a coil spring 57 is arranged, this spring pressing against the end portion of head 58 of the plunger and pushing it against the rear face of the plate 45. This spring 57 is seated within a suitable tube 60 (see Figure 1) and an adjusting screw 61 passing through the rear end of this tube bears against this spring and serves to adjust the pressure which it exerts on the plunger 55. 125 130

Referring to Figure 10, it will be noted that a four hole button similar to that shown in Figures 5 and 6 is being sewed, the parts being so positioned that the sewing is taking place through the rearward pair of holes only as shown at 65. If now it is desired to sew through the forward pair of holes, 66, relative movement must be effected between the button and the sewing instrumentalities. 5

10 It will be noted, however, that as this is a single thread machine, at all times there is either a loop of thread under tension passed through the work from the needle and engaging the looper or else the needle itself 15 is passing through the button and the work. As the motion necessary to cause the stitches to pass through the forward set of two holes can not be accomplished while the needle is in the work, it must be accomplished when 20 the thread is in the work or in the position shown in Figure 10. The thread is then under some tension and therefore offers some resistance to the movement of the button and in some cases it has been found sufficient, 25 with the mechanism shown, to pull the button from its proper position between the clamping jaws. This action is illustrated in Figure 11 in which the button 64 is shown as moved rearwardly in line for the stitches to pass to 30 the forward set of holes 66, as shown by the dotted line 2-2, while the thread passing from the needle extends backwardly through the hole 65 and then forwardly to the looper as shown by the full lines between the same 35 points a-a. In order that the tension on this thread may not in any case act to move the button from its proper position between the jaws, it has sometimes been found useful to employ a light coil spring 70 extending 40 between the side jaws tending to pull them together. In any case the amount of pressure required for this purpose is very slight, the spring 57 being relied upon to impart proper closing tension to the jaws to grip 45 them for the sewing operation.

In order that the jaws may be adjusted away from each other to a sufficient extent to permit the insertion therebetween of any desired size of button a screw 75 is shown as 50 threaded through a block 76 fixed to the rear side of the portion 28 of one of the jaws and impinging at its free end on a similar but solid block 77 on the opposite side jaw. These blocks may be fixed to these jaws by 55 the studs 33 by which the upper ends of the leaf springs 32 are attached and the end of the spring 70 may also be fixed to these same studs. By turning the knurled head 78 of this adjusting screw the spacing of the jaws 60 may be readily accomplished to take the desired size of button.

With this construction it will be seen that 65 this clamp is constructed for holding either two hole or four hole buttons and since members are provided with which the faces of

the buttons may be engaged at three spaced points about its circumference, the buttons are prevented from tilting to such an extent as might interfere with the proper passage of the needle through the sewing holes. For 70 example, a button having a thin portion along one edge as shown in Figure 3 at 90 being supported against tilting is entirely satisfactorily handled in this machine and large thick buttons such as the four hole buttons shown in Figures 5 and 6 may also be successfully handled, the leaf springs for supporting them yielding sufficiently from the flanges 31 of the jaw members to permit them to be entered therebetween. 75

Having thus described an embodiment of this invention it should be evident that various changes and modifications might be made therein without departing from its spirit or scope as defined by the appended claims. 80

I claim:—

1. In a button clamp, a button engaging jaw shaped to engage the top of a button, a member resiliently urged upward into engagement with the lower face of the button, 90 and means to limit the extent to which said member may be moved downwardly relatively to said jaw.

2. In a button clamp, a button engaging jaw having a lip overlying the button, a lip underlying the button and resiliently urged toward the overlying lip, and a positive stop for limiting the amount to which said lips may be separated. 95

3. In a button clamp, a button engaging jaw shaped to engage the edge of the button, and a resilient member fixed to said jaw and having a lip projecting beneath the button engaged by said jaw and a portion projecting over the upper face of said jaw to 100 limit the extent to which said lip and the button-engaging portion of said jaw may be separated. 105

4. A button clamp comprising a jaw formed of a bar bent downwardly, forwardly and then inwardly and formed on its inwardly directed end to engage the edge of a button, and a spring arm made fast to the rear face of said downwardly bent portion, underlying said forwardly and inwardly 110 directed portions and normally pressing upwardly thereagainst and projecting beneath the button, said arm having a finger portion projecting over a portion of said jaw and normally spaced therefrom and serving 115 as a stop to limit the distance to which the button-engaging portion of said arm may be moved downwardly relatively to said jaw. 120

5. A button clamp comprising a jaw formed of a bar bent downwardly, forwardly and then inwardly and formed on its inwardly directed end to engage the edge of a button and having a lip extending over the upper face of the button, and a spring arm made fast to the rear face of said down- 125

65 130

wardly bent portion, underlying said forwardly and inwardly directed portions and normally pressing upwardly thereagainst and projecting beneath the button, said arm having a finger portion projecting over a portion of said jaw and normally spaced therefrom and serving as a stop to limit the distance to which the button-engaging portion of said arm may be moved downwardly relatively to said jaw.

6. A button clamp comprising a jaw formed of a bar bent downwardly, forwardly and then inwardly and formed on its inwardly directed end to engage the edge of a button and having a lip extending over the upper face of the button, a spring arm made fast to the rear face of said downwardly bent portion, underlying said forwardly and inwardly directed portions and normally pressing upwardly thereagainst and projecting beneath the button, said arm having a finger portion projecting over a portion of said jaw and normally spaced therefrom and serving as a stop to limit the distance to which the button-engaging portion of said arm may be moved downwardly relatively to said jaw, said spring arm projecting beyond said lip.

7. A button clamp comprising a jaw formed of a bar bent downwardly, forwardly and then inwardly and formed on its inwardly directed end to engage the edge of a button and having a lip extending over the upper face of the button, a spring arm made fast to the rear face of said downwardly bent portion, underlying said forwardly and inwardly directed portions and normally pressing upwardly thereagainst and projecting beneath the button, said arm having a finger portion projecting over a portion of said jaw and normally spaced therefrom and serving as a stop to limit the distance to which the button-engaging portion of said arm may be moved downwardly relatively to said jaw, said spring arm projecting beyond said lip, and means for guiding the button-engaging portion of said arm relative to said jaw.

8. A button clamp comprising a jaw formed of a bar bent downwardly, forwardly and then inwardly and formed on its in-

wardly directed end to engage the edge of a button and having a lip extending over the upper face of the button, a spring arm made fast to the rear face of said downwardly bent portion, underlying said forwardly and inwardly directed portions and normally pressing upwardly thereagainst and projecting beneath the button, said arm having a finger portion projecting over a portion of said jaw and normally spaced therefrom and serving as a stop to limit the distance to which the button-engaging portion of said arm may be moved downwardly relatively to said jaw, and a pin projecting upwardly from the forward portion of said arm and guided in an opening in said jaw.

9. A button clamp comprising a jaw formed of a bar bent downwardly, forwardly and then inwardly and formed on its inwardly directed end to engage the edge of a button and having a lip extending over the upper face of the button, a spring arm made fast to the rear face of said downwardly bent portion, underlying said forwardly and inwardly directed portions and normally pressing upwardly thereagainst and projecting beneath the button, said arm having a finger portion projecting over a portion of said jaw and normally spaced therefrom and serving as a stop to limit the distance to which the button-engaging portion of said arm may be moved downwardly relatively to said jaw, said spring arm projecting beyond said lip, and means for guiding the button-engaging portion of said arm relative to said jaw.

10. A button clamp comprising a pair of pivoted side jaws, and a rear jaw slidable between said side jaws, a spring for urging said rear jaw forwardly, connections between said side and rear jaws causing forward movement of said rear jaw to effect motion toward each other of said side jaws to bring all of said jaws toward each other, and a spring connecting said side jaws and urging them toward each other.

In testimony whereof I have affixed my signature.

ROBERT L. LYONS.
